PANELED WING CHAIR

David D. Granger, Conover, N.C., assignor to Maxwell Royal Chair Co., Hickory, N.C., a corporation of North Carolina

Continuation-in-part of design application Ser. No. 7,120, May 15, 1967. This application Jan. 15, 1968, Ser. No. 10,162

Term of patent 14 years

(Cl. D15—1)

FIGURE 1 is a front perspective view of a paneled wing chair showing my new design with portions thereof broken away to indicate indeterminate length; and

FIGURE 2 is a side elevational view thereof looking from the right side of FIGURE 1.

The dominant features of my design reside in those portions shown in full lines.

This is a continuation-in-part of design application Ser. No. 7,120, filed May 15, 1967.

I claim:

The ornamental design for a paneled wing chair, as shown and described.
